(57) **CLAIM**

The ornamental design for a wire basket for packaging
sporting equipment, as shown and described.

DESCRIPTION

FIG. 1 is a perspective view illustrating a wire basket for
packaging sporting equipment;

FIG. 2 is a front view thereof;

FIG. 3 is a left side elevational view thereof;

FIG. 4 is a right side elevational view thereof;

FIG. 5 is a top view thereof;

FIG. 6 is a rear view thereof; and,

FIG. 7 is a bottom view thereof.

The broken line showing of environment in the drawings is
for illustrative purposes only and forms no part of the
claimed design.
